UNITED STATES PATENT OFFICE.

ANDREW A. JOHANSON, OF CORDOVA, TERRITORY OF ALASKA.

CAN-OPENER.

1,331,437.

Specification of Letters Patent. Patented Feb. 17, 1920.

Application filed July 3, 1919. Serial No. 308,504.

To all whom it may concern:

Be it known that I, ANDREW A. JOHANSON, residing at Cordova, Territory of Alaska, have invented new and useful Improvements 5 in Can-Openers, of which the following is a specification.

This invention relates to kitchen tools, particularly to can openers, and has for its object the provision of a device adapted to 10 be secured either upon a wall or upon a table or shelf, and which is adapted to punch diametrically opposite holes in the top of a well known tin can used for containing evaporated milk, it being customary in the 15 use of such cans to merely punch two holes with some convenient implement instead of removing the top of the can as is done with cans of other materials.

An important object is the provision of a 20 device of this character which will be very simple and inexpensive in manufacture, which will itself support a can while the top thereof is being punched, which will consequently be easy to operate, efficient in service, 25 durable in use, and a general improvement in the art.

With the above and other objects and advantages in view, the invention consists in the details of construction to be hereinafter 30 more fully described and claimed, and illustrated in the accompanying drawings, in which—

Figure 1 is a side elevation of the device, showing a can engaged therein and the penetrating members in initial position,

Fig. 2 is a plan view thereof,

Fig. 3 is a horizontal sectional view on the line 3—3 of Fig. 1,

Fig. 4 is a longitudinal sectional view on 40 the line 4—4 of Fig. 1 with the can removed, and

Fig. 5 is a longitudinal sectional view taken at right angles to Fig. 4 and showing the penetrating members in entered position.

Referring more particularly to the drawings, the numeral 10 designates the relatively 45 stationary portion of the device which is formed as a vertical support 11 formed arcuate in cross section and provided with holes 12 adapted for the passage of screws or the like whereby the device may be secured upon the wall. At its lower end, the support 10 has formed thereon or secured thereto, a circular platform 13 which is provided with 50 holes 14 adapted for the passage of screws or the like whereby the device may be se-

cured upon a table or shelf instead of a wall, if preferred. At its juncture with the platform 13, the support 10 is enlarged and widened, as shown at 15, whereby to provide 60 flanges engageable by the periphery of a milk can A, whereby the can will be centered upon the platform 13. At its upper end, the support 11 has formed thereon a bearing eye 16 adapted for the reception of a 65 pivot pin or bolt 17 extending through the spaced arms 18 formed on the end of a punch member 19 which is formed circular in shape with a hollow center and which has its diametrically opposite portion elongated to provide a shank 20 secured within the end of a handle 21. By this construction it will be seen that the punch member 19, together with the handle 21 may be swung in a vertical plane upon the pivot bolt 17, as an axis. 70

At their sides, the arms of the punch member 19 have formed thereon laterally extending ears 22 which are apertured for the passage of rivet members 23 or the like formed on the upper ends of conical penetrating members 24 which extend downwardly below the punch member 19 and which are arcuate in shape, as shown, with their axes concentric with the pivot point 17.

The supporting member 10 and the platform 13, and also the punch member 19, may be formed of sheet metal, stamped and bent to proper form, if desired, though it will be understood that the parts may be cast or otherwise formed, if desired, it being a non essential part of the invention, which method of construction be employed.

In the operation of the device, the can A to be punched or opened, is set upon the platform 13 with its periphery engaging 95 against the supporting member 11, it being understood that the punch member 19 and handle 21 are initially so swung forwardly that the penetrating members 24 will be in non obstructing position with relation to the can. After the can is thus positioned, the operator grasps the handle 21 and forces the same downwardly, whereupon the penetrating members 24 will engage and then enter the top of the can at diametrically 100 opposite points whereby to form two holes therein, one serving for the admission of air and the other serving as a discharge opening for the contents of the can.

From the foregoing description and a 110 study of the drawings, it will be apparent that I have thus provided an extremely sim-

ple device which will be inexpensive in manufacture, which may be readily and easily attached to a table, shelf, wall, or other support, and which is operable whereby to 5 punch two holes in the top of a can of evaporated milk and the like.

While I have shown and described the preferred embodiment of my invention, it is of course to be understood that I reserve 10 the right to make such changes in the form, construction, and arrangement of parts as will not depart from the spirit of the invention or the scope of the subjoined claim.

Having thus described my invention, I 15 claim:—

A device of the character described comprising a vertical support, a circular horizontal platform on the lower end of said support, the juncture of said support with

said platform being enlarged and widened 20 to provide vertically disposed guide flanges engageable by a can disposed upon said platform whereby said can will be properly centered upon said platform, a bearing eye formed at the upper end of said support, a 25 punch member in the nature of an open centered yoke having at one side arms straddling and pivotally connected with said bearing eye, said yoke being provided at a point opposite said arms with a shank, a 30 handle engaged upon said shank, and a pair of penetrating members extending from the underside of said punch member at diametrically opposite sides thereof, said penetrating members being arcuate in shape with 35 their axes concentric with said pivot point.

In testimony whereof I affix my signature.

ANDREW A. JOHANSON.
